UNITED STATES PATENT OFFICE.

WILLIAM BROWN, OF ST. LOUIS, MISSOURI, ASSIGNOR TO LAURA A. BROWN, OF ST. LOUIS, MISSOURI.

FAN.

Application filed October 14, 1921. Serial No. 507,643.

To all whom it may concern:

Be it known that I, WILLIAM BROWN, a citizen of the United States, residing at the city of St. Louis, Missouri, have invented a new and useful Improvement in Fans, of which the following is a specification.

This invention relates to fans.

An object of the invention is to provide a fan of a novel and improved construction in which the fan blade is composed of paper or pasteboard of a novel shape or form and having a notch for receiving the fan handle, in combination with a handle having a slot or kerf at one end to receive the edge of the fan blade, the width of the handle at the bottom of the slot or kerf being approximately equal to the width of the notch in the fan blade, and a fastening element passing through the blade embracing portions of the handle and through the interposed blade relatively close to the edge of the blade at the bottom of the notch.

By this construction I am enabled to use a relatively short handle having short blade-engaging portions so that a single fastener may be employed to secure the handle to the fan blade, and this single fastener may be located very close to the marginal edge of the blade. Further, by constructing the blade in the manner stated and as hereinafter more fully disclosed, and by securing the handle thereof as herein shown and described, the desired flexibility of the fan blade is maintained, and still the fan blade possesses sufficient strength to prevent breaking, which result has heretofore been obtained by employing one or more overlapping portions of the handle extending to or beyond the center of the blade.

In the fans in which long portions of the handle extend approximately to or beyond the center of the fan blade, it has been necessary to employ a fastener, usually a staple passed through the extended part of the handle and through the fan blade and clamped, that is to hold the blade and the extended part of the handle together to obtain the necessary strength. In such cases the clamped staple for the end of the extended handle often becomes caught or entangled in the clothing of the user, particularly in fine fabrics, breaking one or more of the threads.

A fan of my improved construction obtains the necessary strength in the fan blade and at the same time, avoids the necessity of using a long overlapping portion of the handle to obtain that strength; and, in addition, my invention avoids the use of the objectionable staple or fastener in connection with the long overlapping portion of the handle, thus providing a fan which is not subject to any of the objections stated and does not become caught or entangled in the clothing of the user.

Another object of my invention is to provide an improved fan, comprising a fabricated blade and a separate handle attached thereto, which is not subject to any of the objections mentioned.

Fig. 1 is a side elevation of my improved fan.

Fig. 2 is a sectional view on the line 2—2 of Fig. 1.

In the embodiment shown the blade 1 is composed of paper or other fibrous, fabricated material. The blade 1 may be of any desired shape, subject, however, to the fact that it must necessarily contain the notch in one side thereof, as hereinafter described. At the lower side edge of the blade 1 a notch is formed, the side walls 2 of which curve on convex lines to an intersection with the bottom wall 3 of said notch. As shown, the bottom wall 3 is at right angles to the longitudinal or vertical axis of the fan. The notch thus formed is of sufficient depth to leave the relatively long downwardly extended ears or side portions 4, which extend downwardly, a relatively considerable distance below the bottom wall 3 of the notch.

The fan handle 5 is composed of wood or other appropriate material and is provided with a portion 6 at one end having a width equal to the width of the bottom of the notch formed in the fan blade; that is, the width of the portion 6 is equal to the length of the bottom wall 3 of the notch.

The part 6 of the fan handle is provided with a notch or kerf 7 therein, the width of which is about equal to the thickness of the fan blade and the depth of which is relatively shallow. This provides two short side members adapted to receive the edge of the fan blade between them. The bottom wall of the notch 7 fits against the bottom wall 3 of the notch in the fan blade, the width of the part 6 of the handle at the bottom of

the notch 7 being equal to the width of the notch in the fan blade. The length of the side members of the handle need not exceed the width thereof, since, as a result of the novel construction and relationship of parts, the necessary strength and rigidity is obtained without the use of long or extended handle members engaging the fan blade. A fastener 8 passes through the side members of the handle and through the interposed portion of the fan blade clamping the parts together. As shown, the fastener 8 is in the form of an eyelet whose flared or swaged ends 9 are countersunk in the handle, thus leaving no projections to become caught or entangled with the clothing of the user of the fan, or with other fabrics.

Fans of this improved construction have been used with complete satisfaction, and as a result of such actual use, I have found that all of the intended objects and purposes of the invention are obtained and all of the objections heretofore mentioned are avoided.

What I claim and desire to secure by Letters Patent is:—

1. A fan, comprising a flexible blade composed of fibrous fabricated material having a relatively deep notch in one side edge thereof provided with convex inner walls and a wide bottom intersecting the convex walls of said notch, in combination with a handle having a shallow slot in one end thereof receiving the edge of the fan blade at the bottom of said notch, the sides of the handle on opposite sides of the fan blade terminating only a short distance above the bottom of the notch in the fan blade, and a fastener passing through the side portions of the handle and through the interposed portion of the fan blade a short distance above the bottom wall of said notch and near the bottom edge of the fan blade.

2. A fan, comprising a flexible blade composed of fibrous fabricated material having a relatively deep and wide notch in one side edge thereof provided with a wide bottom intersecting the side walls of said notch, in combination with a handle having a shallow

slot in one end thereof receiving the edge of the fan blade at the bottom of said notch, the sides of the handle on opposite sides of the fan blade terminating only a short distance above the bottom of the notch in the fan blade, and a fastener passing through the side portions of the handle and through the interposed portion of the fan blade a short distance above the bottom wall of said notch and near the bottom edge of the fan blade, said fastener having its opposite ends countersunk in the handle.

3. A fan of the character described, comprising a paper blade having a notch in one side thereof, the side walls of the notch being convex and the bottom of the notch being relatively wide and at right angles to the vertical axis of the blade, a handle having a portion at one end thereof the width of which is equal to the width of the bottom of the notch, and said portion of the handle having a slot therein of relatively much less depth than one-half of the diameter of the fan blade, said slot receiving the edge of the fan blade at the bottom of said notch, and a fastener passing through the handle and through the interposed portion of the fan blade relatively near the bottom wall of said notch.

4. A fan of the character described, comprising a paper blade having a notch in one side thereof, the side walls of the notch being convex and the bottom of the notch being relatively wide and at right angles to the vertical axis of the blade, a handle having a portion at one end thereof the width of which is equal to the width of the bottom of the notch and said portion of the handle having a slot therein of relatively much less depth than one-half of the diameter of the fan blade, said slot receiving the edge of the fan blade at the bottom of said notch, a fastener passing through the handle and through the interposed portion of the fan blade relatively near the bottom wall of said notch, and the ends of said fastener being countersunk in the handle.

WILLIAM BROWN.
